UNITED STATES PATENT OFFICE.

OTTO W. JOHNSON, OF OAKLAND, CALIFORNIA, ASSIGNOR OF ONE-HALF TO FRED STARR, OF OAKLAND, CALIFORNIA.

SPACING AND FASTENING DEVICE.

Application filed May 9, 1923. Serial No. 637,803.

This invention relates to spacing and fastening devices for metal lath construction, or the like; and its object is to provide a simplified, inexpensive, combined fastening 5 and spacing device for the wire netting thereof. A further object is to provide means for securing the building-paper sometimes used between the plaster and the sheathing.

10 The accompanying sheet of drawings illustrate the invention and in which:

Fig. 1 is a side elevation of the device constructed in accordance with my invention.

15 Fig. 2 is a side elevation of the same device after it has been driven in place.

Fig. 3 is a side elevation of the device in a modified shape.

20 Fig. 4 is a side elevation of the device as shown in Fig. 3 after it has been driven in place.

Fig. 5 is a side elevation of a modification of the device.

25 Fig. 6 is a side elevation of another modification of the device.

Fig. 7 is a side elevation of another modification of the device, showing two spacing members.

30 Fig. 8 is a perspective view of the device of Fig. 1, showing its position in a sectional piece of sheathing and building-paper.

Like numerals of reference designate like parts in the several views. The numeral 1 designates the shank or straight part of the device that is partly driven into the sheathing or wood, 2 designates the part of the device that acts as spacer, 3 is the upper bent part of the device or the crotch that hooks over the netting, 4 is the point or toe, 5 is the foot or heel of the spacer part of the device, 6 designates part of the device reduced in size by notches or by being cut flat so it will bend more readily, 7 is part of the netting in the crotch of the device held in place by the spacer part, 8 designates a 45 piece of building-paper held firmly against the sheathing 9 by the heel of the spacer part.

My invention as here shown is made of round wire, but square or flat metal may be 50 used.

In using my invention, the pointed end of shank 1 is driven through the building paper 8 into the sheathing 9, the point 4 piercing the building-paper and the sheath-

ing, the heel 5 holding building-paper firmly 55 against the sheathing. The resistance offered by heel 5 causes the reduced or weakened parts 6 to bend, thereby causing the spacer 2 to come under the netting 7, holding same securely in crotch 3.

60 In the device of Fig. 5, the spacing part 2 is turned up and is without a point, and the device is driven in as before, until the netting 7 is held firmly in crotch 3.

In Fig. 6, the device is not provided with 65 any weakened parts, but depends on the resistance of heel 5 to cause it to bend.

70 In using the modified device as shown by Fig. 7, the long points 4 are driven into the sheathing, the reduced parts 6 causing the spacer parts 2 to draw together under the netting, holding same firmly in crotch 3.

Having thus described my invention what I claim and desire to secure by Letters Patent, is—

75 1. A wire spacing and fastening device in the form of a two-pronged staple, having one of said prongs provided with a series of bends adapting the prong to close inwardly and upwardly to engage the wire when the 80 said staple is driven home.

85 2. A spacing and fastening device comprising, a shank, a spacing member formed integral with said shank and extending downwardly therefrom, oppositely disposed notches formed in said spacing member whereby said member is bent inwardly and upwardly at its notched points to form gripping means for wire netting when the 90 device is driven home.

95 3. A spacing and fastening device comprising, a shank, a spacing member formed integral with said shank and extending downwardly therefrom and ending in a toe, oppositely disposed notches in said member, a heel formed in said member above the toe, said spacing member adapted to bend inwardly and upwardly at the notched points when driven home, the heel determining the 100 spacing.

105 4. In combination, a sheathing, a wire netting spacing and fastening device comprising a shank, a spacing member formed integral with said shank and extending downwardly therefrom and provided with a toe at the lower end thereof, and notches formed in said spacing member intermediate thereof and adapted to bend said member

inwardly when driven home to engage the netting, the toe engaging the sheathing to prevent slippage.

5. In combination, a sheathing, a spacing and fastening device comprising a shank, a spacing member formed integral with said shank and extending downwardly therefrom and provided with a toe and heel at the lower end thereof, oppositely disposed notches formed in the spacing member adapted to bend the said member inwardly and upwardly when driven home to form a gripping and spacing means for a wire netting, the toe preventing slippage and the heel determining the spacing.

6. A lath staple comprising a single

length of wire having one end formed into a driven element terminating at its upper end into a lateral extension, and its other end bent to form lath spacing means disposed below said extension, and a connection between said lath spacing means and the outer end of said extension, said connection having a portion substantially reduced in cross section in the plane of the staple and adapted to operatively bend when said lath spacing means engages the support into which said driven element is operatively projected a proper distance.

In testimony, that I claim the foregoing as my invention, I have signed my name.

OTTO W. JOHNSON.
